[57] CLAIM

The ornamental design for luggage, substantially as shown and described.

DESCRIPTION

FIG. 1 is a front elevational view of luggage showing my new design;

FIG. 2 is a top plan view thereof;

FIG. 3 is a rear elevational view thereof;

FIG. 4 is a bottom plan view thereof;

FIG. 5 is a side elevational view looking from the left of FIG. 1; and

FIG. 6 is a side elevational view looking from the right of FIG. 1.

The stippling and the fabric texture indication on the drawings are used to show that the luggage of the subject invention has three contrasting colors and not to indicate any specific color or fabric.
